WEATHER STRIP

Alfred M. Lane, St. Louis County, Mo., assignor
to Monarch Metal Weatherstrip Corporation,
St. Louis, Mo., a corporation of Missouri

Application July 3, 1935, Serial No. 29,587

4 Claims. (Cl. 20—69)

This invention relates to weatherstrips, particularly metal weatherstrips for windows or doors having swinging closures. The principal object of the present invention is to provide a simple and efficient weatherstrip for the joint between the sill and the swing-closure. Other objects are cheapness of construction, compactness of design and ease of installation. The invention consists in the weatherstrip and in the arrangements and combinations of parts hereinafter described and claimed.

In the accompanying drawing, which forms part of this specification and wherein like symbols refer to like parts wherever they occur,

Fig. 1 is an enlarged vertical cross-section through the lower portion of a casement window provided with a weatherstrip embodying my invention; and

Fig. 2 is a fragmentary horizontal cross-section through the outer portion of the sill strip on the line 2—2 in Fig. 1.

The accompanying drawing illustrates a casement window construction equipped with a metal weatherstrip embodying my invention. Said casement window construction comprises a sill or bottom frame member 1, which is provided with the usual stool 1a and an inwardly swinging sash 2 adapted in closed position to overhang said stool. The joint between the sash 2 and the sill 1 is weatherproofed by means of a metal weatherstrip comprising a rigid frame or sill strip A, a resilient closure or sash strip B and a rigid water table or drip strip C. The sill strip A is of substantially trough or channel-shaped cross-section, that is, it comprises a web or base portion 3 that rests on and is screwed or otherwise removably secured to the window stool 1a and is provided along its inner and outer side edges with upwardly extending flanges 4 and 5, respectively, that cooperate with said web to form said trough or channel. The inner side marginal flange 4 of the sill strip A is a vertical flange that is preferably disposed substantially flush with the inner face of the sash 2 in the closed position thereof and is extended below the bottom or base portion 3 of said strip so as to rest on the window sill 1 inside the stool 1a thereof.

The web 3 of the sill strip is offset downwardly outwardly of the window stool 1a and the closed sash 2; and is provided with weep holes 3a, and the outer marginal flange 5 of said sill is inclined upwardly and inwardly toward the lower outside corner of the closed sash and terminates above the plane of the bottom thereof in an arcuate portion which forms a longitudinal groove 6 in

the sash opposing face of said flange. To prevent blocking of the weep holes 3a by the formation of bubbles thereover, I prefer to make such holes of elongated shape, the greater dimension being at least three times greater than the smaller dimension and also larger than the maximum diameter of said bubbles.

The resilient sash strip B comprises a main body portion 7 that is rigidly secured flatwise along its upper margin to the outer face of the sash 2 and terminates at its free lower margin in a curled sealing edge or hollow bead 8 adapted to resiliently engage the groove 6 in the sash opposing face of the outer flange 5 of the rigid sill strip when the sash is closed. The sash strip 15 is provided just above the upper edge of the outer flange 5 of the sill strip with an outstanding longitudinal fold 9 which overhangs said edge of said flange in the closed position of the sash.

The water table or drip strip C is screwed or otherwise secured along its upper margin to the sash 2 and is of such section as to overhang the joint between the sash strip B and the sill strip A and prevent any water which runs down the outer face of said sash from entering said joint. 25

The hereinbefore described weatherstrip has numerous advantages. The parts forming the weatherstrip may be quickly and easily applied without material alteration of the sill or sash. When the sash is closed, the strip P thereon bears 30 resiliently against the groove 6 in the upper edge of the outside flange 5 of the sill strip A and serves as a seal to prevent air, dust and water from being forced through the joint; and the longitudinal folded portion 9 of the sash strip permits 35 the sash to shrink and swell without affecting the joint between the sash strip and the sill strip. The water table C prevents water from running down the outer face of the sash and entering the joint between the sash strip and the sill strip. 40 Any water that may leak through the joint between the sash strip and sill strip will be caught in the trough of the sill strip and promptly discharged therefrom through the weep holes 3a in the downwardly offset bottom of said trough. 45 Likewise, any water that seeps down between the sash pane and the putty and flows through the tenon joints of the sash back of the joint between the sash strip and the sill strip will drip into the shallow portion of the trough thereof and thence 50 flow into the deeper outside trough and be discharged through the weep openings in the bottom thereof upon the sill. Making the weep holes longer in one direction than the maximum diameter of the bubble that will be formed in the 55

trough of the sill strip eliminates the possibility of such a bubble forming over any weep hole and blocking drainage therethrough.

It is evident that the invention may be applied 5 to the sills of doors and other closure members; and it is not restricted to the precise shape and arrangement of parts shown in the drawing.

What I claim is:

1. The combination with an inwardly swinging 10 closure and a sill therefor, of a weatherstrip comprising two members mounted on the sill and on the closure, respectively, the sill member comprising a strip of rigid metal having a trough therein disposed beneath said closure in closed 15 position thereof with its outer wall located outwardly of the closed closure, the closure member comprising a strip of resilient metal secured along its upper margin only to the outer face of said closure and having a free lower marginal portion spaced from and adapted in the closed 20 position of said closure to yieldably engage said outer wall of the trough in said sill strip, said closure member being provided with an outstanding longitudinal fold that overhangs the free 25 lower marginal portion thereof, and a drip strip secured to the outer face of said closure and overhanging the sill strip engaging margin of said closure strip and said longitudinal fold.

2. The combination with an inwardly swinging 30 closure and a sill therefor, of a weatherstrip comprising two metal strips mounted on the sill and on the closure, respectively, the sill strip comprising a bottom portion with an upwardly extending inner side marginal flange located in the closed position of said closure near the inner 35 face thereof and an upwardly extending outer side marginal flange located outwardly of said closure in the closed position thereof, the inner face of said outer flange being provided above the plane of the bottom of said closure with a longitudinal groove, said sill strip being provided adjacent to said outer flange with weep holes, the closure strip comprising a strip of resilient metal secured along its upper edge to the outer face of said closure and having its lower edge left free and formed into a bead for engagement with the 40 groove in the outer flange of said sill strip in the closed position of said closure, said closure strip being provided with an outstanding longitudinal 45

fold that overhangs the upper edge of the outer flange of said sill strip.

3. The combination with an inwardly swinging closure and a sill therefor, of a weatherstrip comprising two metal strips mounted on the sill and on the closure, respectively, the sill strip comprising a bottom portion with an upwardly extending inner side marginal flange located in the closed position of said closure near the inner face thereof and an upwardly extending outer side marginal flange located outwardly of said closure in the closed position thereof, the inner face of said outer flange being provided above the plane of the bottom of said closure with a longitudinal groove and the bottom of said sill strip being provided adjacent to said outer flange with weep holes, the closure strip comprising a strip of resilient metal secured along its upper edge to the outer face of said closure and having a free lower edge formed into a bead spaced from 20 said face and adapted to yieldably engage the groove in the outer flange of said sill strip in the closed position of said closure, and a rigid drip strip secured to the outer face of said closure and overhanging the beaded free lower edge of said 25 closure strip.

4. The combination with an inwardly swinging closure and a sill therefor having a raised stool located beneath said closure in the closed position thereof, of a weatherstrip comprising two metal strips mounted on the sill and on the closure, respectively, the sill strip comprising a bottom portion resting on and secured to said stool and having an inner side marginal flange that extends above and below said bottom portion and rests on said sill inwardly of said stool, and an upwardly extending outer side marginal flange located outwardly of said stool and the outer face of the closed sash, the bottom portion of said sill strip being offset downwardly outwardly of said stool 40 and said closed sash to form a trough provided with weep holes, the closure strip comprising a strip of resilient metal secured along its upper margin to the outer face of said closure and having a free lower margin spaced outwardly from said face and adapted to yieldably engage the outer flange of said sill strip in the closed position of said closure.

ALFRED M. LANE.
